UNITED STATES PATENT OFFICE

140,758

DESIGN FOR A MOTOR AND PUMP ASSEMBLY

Laurie C. Badgley, Chicago, Ill., assignor to
H. Goldberg, Chicago, Ill.

Application January 27, 1945, Serial No. 117,643

Term of patent 14 years

(Cl. D65—1)

To all whom it may concern:

Be it known that I, Laurie C. Badgley, a citizen of the United States, residing at Chicago, in the county of Cook and State of Illinois, have invented a new, original, and ornamental Design for Motor and Pump Assembly, of which the following is a specification, reference being had to the accompanying drawings, forming part thereof,

I claim:

The ornamental design for a motor and pump assembly, substantially as shown.

LAURIE C. BADGLEY.
